UNITED STATES PATENT OFFICE

JOHNSE H. BECK, OF INDIANAPOLIS, INDIANA, ASSIGNOR TO GEO. F. CRAM COMPANY, OF INDIANAPOLIS, INDIANA, A CORPORATION OF ILLINOIS

MAP HOLDER

Application filed November 28, 1927. Serial No. 236,083.

The object of my invention is to provide a simple, cheap and efficient hanger by means of which roll curtain maps may be detachably supported in position for manipulation but prevented from accidental displacement, the construction being such that the map at all times will be supported horizontally.

The accompanying drawings illustrate my invention.

10 Fig. 1 is a front elevation of my improved hanger and supported map; Fig. 2 an end elevation in partial vertical section; Fig. 3 a face view of one of my improved brackets, which forms part of the hanger; Fig. 4 a side elevation of another form of bracket; Fig. 5 15 a front elevation of the structure shown in Fig. 4; Fig. 6 a transverse section on line 6—6 of the structure shown in Fig. 5, and Fig. 7 a partial axial section of the structure shown 20 in Fig. 5 with the parts packed for shipment.

In the drawings 10 indicates a bar of suitable length with its ends 11 and 12 bent substantially at right angles and perforated to receive the ends of an ordinary spring roller 13 upon which the map 14 is secured. Bracket 12 is perforated to rotatably receive the adjacent end of roller 13 while bracket 11 is perforated to non-rotatably receive stem of the adjacent end of roller 13. The ends 11 and 25 12 are bent into proper relationship with the projected ends of roller 13 so as to form a substantially permanent connection between bar 10 and roller 13 and thus prevent accidental displacement.

30 The bar 13 is preferably tubular for the sake of lightness and at two points spaced, preferably equally, from the middle of the bar are short radially projecting shanks or pins 15 having tapered heads 16, the shanks 40 and heads being most conveniently formed from ordinary flat headed screws. In Figs. 2 and 3 I show a suitable supporting bracket for a single map formed for attachment to a vertical wall. This bracket is a piece of sheet 45 metal bent along two transverse lines to form

a wall section 20, a map-supporting section 21 spaced from the wall and intermediate section 22. Section 21 is provided with two spaced perforations 23, 23 of proper size and spacing to permit the entry of the heads 16 of the two shanks 15. Communicating with perforations 23 are two downwardly divergent slots 24, 24 whose diameters are slightly greater than the diameters of the shanks 15 and whose lower ends are spaced apart a distance equal to the spacing of the two shanks 15, the arrangement being such that the rod 10 may not be moved squarely, vertically upwardly, the construction thus preventing accidental displacement.

In order to assemble the rod 10 with the bracket the heads 16 are projected laterally through the openings 23 and the shanks 15 then swung alternately down into the slots 24. Removal of the rod is accomplished by a reverse operation.

It is often desirable to support a group of maps for convenient access and for this purpose I provide the bracket shown in Figs. 4 to 7 inclusive, the metal strip 30 being provided with a plurality of pairs of perforations 23—24, as previously described. This strip may be conveniently and cheaply braced by brazing a light channel 31 to its rear face between the perforations. The lower end of strip 30 is bent into a pocket 32 in which may be supported a hook rod 33 which may be used to reach the higher maps. The upper end of strip 30 is bent radially, as indicated at 34 and is perforated so that one end of an L-shaped strut 35 may be detachably secured thereto by bolts 36, the foot of bracket 35 being attachable to a wall as shown, and the construction being such that the parts may be nested, as shown in Fig. 7, for convenient shipping.

I have found that by making the under surfaces of heads 16 of shanks 15 tapered instead of square, the tendency of the edges of these surfaces to bite into the supporting

bracket, is so minimized as to avoid trouble.

The provision of the two laterally spaced shanks insures maintenance of the map-supporting rod in horizontal position when the parts are not in use, thus avoiding unsightliness.

When a map is being manipulated any off-center pull, tending to rock the map-supporting rod on a horizontal axis, is compensated because the map-supporting rod tends to swing upon the nearest shank and the subsequent un-supported weight of the long end of the rod and supported map have a strong tendency to overcome the off-centered pull. Any such off-centered pull however, because of the peculiar arrangement of the slots, does not permit either head to be brought into such position relative to its perforation that the head can be pulled laterally from the bracket. All possibility of accidental displacement of the map-supporting rod is thus obviated.

I claim as my invention:

1. A map support comprising a roller-supporting rod having two laterally projecting headed shanks arranged upon opposite sides of the middle of the rod and intermediate of the ends, and a supporting bracket having a pair of keyhole slots, the upper ends of which are large enough to receive the shank heads and the depending shanks of which are large enough to receive the shanks but smaller than the heads, said slots and shanks being so arranged that the rod may pivot on either shank.

2. A map support comprising a roller-supporting rod having two laterally projecting tapered headed shanks arranged upon opposite sides of the middle of the rod and intermediate of its ends, and a supporting bracket having a pair of keyhole slots, the upper ends of which are large enough to receive the shank heads and the depending shanks of which are large enough to receive the shanks but smaller than the heads, said slots and shanks being so proportioned and arranged that the rod may pivot on either shank.

3. A map support comprising a roller-supporting rod having two laterally projecting headed shanks arranged upon opposite sides of the middle of the rod, and a supporting bracket having a pair of keyhole slots, the upper ends of which are large enough to receive the shank heads and the depending shanks of which are large enough to receive the shanks but smaller than the heads, and are downwardly divergent with their upper ends closer together than the distance between the shanks.

4. A map support comprising a roller-supporting rod having two laterally projecting tapered headed shanks arranged upon opposite sides of the middle of the rod, and a supporting bracket having a pair of keyhole slots, the upper ends of which are large

enough to receive the shank heads and the depending shanks of which are large enough to receive the shanks but smaller than the heads, and are downwardly divergent with their upper ends closer together than the distance between the shanks.

In witness whereof, I have hereunto set my hand at Indianapolis, Indiana, this 17th day of November, A. D. one thousand nine hundred and twenty-seven.

JOHNSE H. BECK.
